UNITED STATES PATENT OFFICE.

JAMES M. WOOD, OF KANSAS CITY, MISSOURI; SAM B. STROTHER, ADMINISTRATOR OF SAID WOOD, DECEASED, ASSIGNOR TO KATHLEEN G. SMITH, OF KANSAS CITY, MISSOURI.

SEISMOMETER.

No. 923,397.

Specification of Letters Patent.

Patented June 1, 1909.

Application filed October 21, 1907. Serial No. 398,465.

To all whom it may concern:

Be it known that I, JAMES M. WOOD, a citizen of the United States, residing at Kansas City, in the county of Jackson and State 5 of Missouri, have invented certain new and useful Improvements in Seismometers, of which the following is a specification.

My invention relates to an improvement in seismometers.

10 The object of my invention is to provide a novel apparatus for measuring undulations to earthquake shocks or other concussions and denoting the relative dynamic energy of such undulations.

15 My invention is further adapted for use in determining the condition of a railway track.

The novel features of my invention are hereinafter fully described and claimed.

20 In the accompanying drawings illustrative of my invention—Figure 1 is a top view of the apparatus, a portion of the supporting frame being broken away. Fig. 2 is a vertical transverse sectional view taken on the dotted line *a*—*b* of Fig. 6. Fig. 3 is a transverse vertical sectional view taken on the dotted line *c*—*d* of Fig. 6. Fig. 4 is a vertical sectional view taken on the dotted line *e*—*f* of Fig. 6. Fig. 5 is a detail view showing a modification in which a weight instead 25 of a spring is employed to retract the indicating tape. Fig. 6 is a vertical sectional view taken on the dotted line *g*—*h* of Fig. 1.

Similar characters of reference denote similar parts.

35 1 denotes a rectangular framework to the inner side of one vertical end of which is secured one end of a substantially horizontal, vertically resilient and oscillatory bar 2.

40 3 denotes a horizontally resilient bar secured at one end to the opposite end of the frame 1. The bars 2 and 3 are both preferably flat bars, the former having its edges in the same horizontal plane while the latter has its upper and lower edges disposed in a 45 vertical plane.

45 4 denotes two weights mounted respectively upon the oscillatory bars 2 and 3 adjacent the free ends of said bars.

50 5 denotes a longitudinally movable metal tape, one end of which is secured to the periphery of a drum 5' mounted on a rotary horizontal shaft 6 supported in a framework 7, which in turn is supported upon the inner side of one vertical side of the frame 1. The 55 other end of the tape extends through a ver-

tical slot on the inner side on the block 8 secured at its lower end to the upper side of the frame 1.

9 denotes a vertical plate secured to the forward side of said block 8 and extending partly across the slot in the said block so as to retain the tape in said slot or groove. One edge of the tape 5 is provided with ratchet teeth 10 in which respectively engage the free ends of two spring pawls 11 and 12.

The spring pawl 11 is carried by the bar 2 and when oscillated therewith moves the tape 5 lengthwise in a vertical upward direction. The pawl 11 is supported upon one end of a substantially horizontal plate 13, the other end of which is secured to a clip 14 mounted on the bar 2. The pawl 12 is secured to a bracket 15 supported upon the adjacent vertical side of the frame 1. Extending through the said side of the frame 1 is a horizontal rotary shaft 16 to the periphery of which is secured one set of ends of two cords 17 and 18, the other set of ends of which is secured respectively to the pawls 12 and 11 adjacent their free ends. By rotating the shaft 16 in the proper direction the spring pawls 11 and 12 may be released from engagement with the teeth 10 of the tape 5 so that the tape 5 may be retracted after it has been moved lengthwise by the oscillations of the bar 2. Any desired means for rotating the shaft 6 so as to retract the tape 5 may be employed.

In the form shown in Figs. 1 and 6 a spring is employed for this purpose, while in the modification shown in Fig. 5 a weight is employed to retract the tape.

In the form shown in Figs. 1 and 6 a pinion 19 is secured on the shaft 6 and meshes with a spur gear 20 rotatively mounted on the horizontal shaft 21, which in turn is rotatively mounted in the frame 7. Secured to the shaft 21 is a ratchet wheel 22 in the teeth of which engages a pawl 23, secured to the spur gear 20. A coil spring 24 has one end secured to the shaft 21, the other end being secured to the frame 7. When the shaft 21 is rotated in the proper direction the spring 24 will be wound and will exert a pressure tending to rotate the spur gear 20 and through it and the pinion 19 the shaft 6 so as to wind the tape 5 on the drum 5'.

Rotatively mounted in the vertical sides of the frame 1 is a shaft 25 provided with a central crank portion 26 by which, when the shaft 25 is turned to the proper position

pawls 23, 23', and shafts 21 and 21', are dispensed with. On the shaft 6, or 6', as the case may be, a drum 44 is mounted. Secured to the periphery of the drum is one end 5 of a cord 45, the other end of which is attached to a weight 46. The cord 45 is so disposed on the drum 44 that the weight 46 will exert a pressure tending to wind the tape 5, or 30, as the case may be, on the 10 drum 5' or 31. The construction above described is illustrated in Fig. 5.

In the operation of my invention the instrument is disposed with the bar 3 in the horizontal position, the shafts 25 and 42 being turned to the positions, as represented in Figs. 2 and 6. This being done the bars 2 and 3 are free to oscillate in vertical and horizontal directions respectively. Vertical undulations due to earthquake shocks will 15 cause vertical oscillation of the weight 4 on the bar 2 relative to the frame 1. Such oscillation of the bar 2, will, as has been already described, reciprocate the pawl 11, thus forcing the tape 5 from its initial position upward a distance corresponding to the number and extent of the oscillations of the bar 2. In a corresponding manner the bar 3 will be oscillated in a horizontal plane by undulations traveling in a horizontal plane. Such 20 oscillations of the bar 3 will force upward the tape 30 a distance corresponding to the extent and number of the oscillations of the bar 3, as has already been described.

To determine the condition of a railway 35 road bed and track the instrument is placed with the bar 3 in a horizontal position upon a car and the car run over the track to be tested. Vertical and horizontal oscillations of the car, due to inequalities in the track, 40 will be transmitted respectively to the bars 2 and 3. The oscillations of the bars 2 and 3 will, as has already been described, move the tapes 5 and 30 respectively in an upward direction, distances corresponding to the extent and number of oscillations. By comparing the distances moved by the tapes 5 and 30 with the distances the tapes move 45 when the car is run over a corresponding length of good track the relative condition of the track to be tested may be determined.

Various modifications, within the scope of the appended claims, may be made in my invention without departing from its spirit.

Having thus described my invention, what 55 I claim and desire to secure by Letters Patent is:—

1. In a seismometer, the combination with an oscillatory support, of a weight carried by said support, a lengthwise movable tape, 60 means actuated by said support by which said tape is moved lengthwise in one direction when said support is oscillated, means for normally holding the tape against retraction and means for retracting said tape 65 in the opposite direction.

2. In a seismometer, the combination with an oscillatory support, of a weight carried by said support, a longitudinally movable tape, means actuated by said support by which said tape is moved lengthwise in one direction when said support is oscillated, means for indicating the distance moved by such tape in said direction, means for normally holding the tape against retraction and means for retracting the tape in the opposite direction.

3. In a seismometer, the combination with an oscillatory support, of a weight carried by said support, a longitudinally movable tape, and a device oscillative with said support for moving the tape lengthwise in one direction when said support is oscillated.

4. In a seismometer, the combination with an oscillatory support, of a weight carried by said support, a longitudinally movable tape, a device oscillative with said support for moving the tape lengthwise in one direction when said support is oscillated, and means for indicating the distance moved by such tape in said direction.

5. In a seismometer, the combination with an oscillatory support, of a weight carried by said support, a longitudinally movable tape, a device oscillative with said support for moving the tape lengthwise in one direction when said support is oscillated, means for indicating the distance moved by such tape in said direction, means for normally holding the tape against retraction and means for retracting the tape in the opposite direction.

6. In a seismometer, the combination with an oscillatory support, of a weight carried by said support, a longitudinally movable tape having a series of transverse graduations, an indicator for successively indicating such graduations when the tape is moved lengthwise, and means actuated by said support by which said tape is moved lengthwise in one direction when said support is oscillated.

7. In a seismometer, the combination with an oscillatory support, of a weight carried by said support, a lengthwise movable tape having a series of transverse graduations, an indicator for successively denoting said graduations when the tape is moved lengthwise, means actuated by said support by which said tape is moved lengthwise in one direction when said support is oscillated, means for normally holding the tape against retraction and means for retracting said tape in the opposite direction.

8. In a seismometer, the combination with an oscillatory support, of a weight carried by said support, a longitudinally movable tape provided with a longitudinal row of ratchet teeth, a pawl carried by said support and engaging with the teeth of said tape for moving the tape lengthwise in one direction when said support is oscillated, and means for indicating the distance moved by said tape.

9. In a seismometer, the combination with oscillatory support, of a weight carried by said support, a longitudinally movable tape provided with a longitudinal row of ratchet teeth, a pawl engaging said ratchet teeth and carried by said support for moving the tape lengthwise in one direction when said support is oscillated, means for retracting the tape in the opposite direction, and a pawl normally holding the tape against retraction.
10. In a seismometer, the combination with an oscillatory support, of a weight carried by said support, a longitudinally movable tape provided with a longitudinal row of ratchet teeth, a pawl engaging said ratchet teeth and carried by said support for moving the tape lengthwise in one direction when said support is oscillated, means for indicating the distance of movement of said tape in the said one direction, means for retracting the tape in the opposite direction, and a releasable pawl for normally holding said tape against retraction.
11. In a seismometer, the combination with an oscillatory support, of a weight carried by said support, a longitudinally movable tape having a longitudinal row of ratchet teeth, two pawls engaging said ratchet teeth, one pawl carried by said support for moving the tape lengthwise in one direction when said support is oscillated, the other pawl normally holding said tape against retraction, means for retracting said tape when said pawls are released therefrom, and means for simultaneously releasing the pawls from engagement with said ratchet teeth.
12. In a seismometer, the combination with an oscillatory support, of a weight carried by said support, a lengthwise movable tape having a row of transverse graduations provided with a longitudinal row of ratchet teeth, an indicator for successively noting said transverse graduations, two pawls engaging said ratchet teeth, one pawl carried by said support for moving the tape lengthwise in one direction when said support is oscillated, the other pawl normally holding the tape against retraction, means for retracting said tape, and means for releasing said pawls from said ratchet teeth.
13. In a seismometer, the combination with an oscillatory support, of a weight carried by said support, a lengthwise movable tape having a longitudinal row of ratchet teeth, two pawls normally engaging said ratchet teeth, one pawl being carried by said support for moving the tape lengthwise in one direction, the other pawl normally holding said tape against retraction in the opposite direction, means for retracting said tape in the opposite direction, indicating means for denoting the distance of movement of said tape, and means for simultaneously re-
- leasing the said pawls from engagement with said ratchet teeth.
14. In a seismometer, the combination with an oscillatory support, of a weight carried by said support, a lengthwise movable tape having a longitudinal row of ratchet teeth, two pawls normally engaging said ratchet teeth, one pawl being carried by said support for moving the tape lengthwise in one direction, the other pawl normally holding said tape against retraction in the opposite direction, means for retracting said tape in said opposite direction, indicating means for denoting the distance of movement of said tape, a rotary shaft and two cords secured at one set of ends to the periphery of said shaft and connected at the other set of ends with said pawls respectively for withdrawing said pawls from engagement with said ratchet teeth when said shaft is rotated in the proper direction.
15. In a seismometer, the combination with an oscillatory support, of a weight carried by said support, a lengthwise movable tape, means actuated by said support for moving the tape lengthwise in one direction when said support is oscillated, releasable means for holding said tape against retraction in the opposite direction, means for retracting said tape in the opposite direction, and releasable means for holding said support against oscillation.
16. In a seismometer, the combination with two supports oscillative in planes at right angles to each other, of two weights carried by said supports respectively, two lengthwise movable tapes, and means actuated by said supports respectively by which said tapes are moved lengthwise in one direction when said supports are respectively oscillated.
17. In a seismometer, the combination with two supports oscillative in planes at right angles to each other, of two weights carried by said supports respectively, two lengthwise movable tapes, means actuated by said supports respectively by which said tapes are moved lengthwise in one direction when said supports are respectively oscillated, and two indicating means for denoting the distance moved by said tapes respectively.
18. In a seismometer, the combination with two supports oscillative in planes at right angles to each other, of two weights carried by said support respectively, two lengthwise movable tapes means actuated by said supports respectively by which said tapes are moved lengthwise respectively in one direction when said supports are oscillated, means for normally holding the tape against retraction and means for retracting said tapes in the opposite direction.
19. In a seismometer, the combination with two supports oscillative in planes at

right angles to each other, of two weights carried by said supports respectively, two lengthwise movable tapes, means actuated by said supports respectively by which said 5 tapes are moved lengthwise respectively in one direction when said supports are respectively oscillated, separate means for normally holding said tapes against retraction, 10 separate means for respectively retracting said tapes, two indicating means for denoting the lengthwise movement of said tapes, and means for releasing said tapes from said holding means.

20. In a seismometer, the combination 15 with a support oscillative in a vertical plane, of a weight carried by said support, a lengthwise movable tape having a longitudinal row of ratchet teeth, and a reciprocative pawl engaging said ratchet teeth actuated by said 20 support.

21. In a seismometer, the combination 25 with an oscillatory support, of a weight carried by said support, an indicating tape, means for moving said tape lengthwise in one direction when the said support is oscillated, releasable means for holding said tape from

moving lengthwise in the opposite direction, a spring, and means by which when the tape is released from said holding means, the spring will retract said tape in said opposite direction.

22. In a seismometer, the combination with an oscillatory support, of a weight carried by said support, an indicating tape having a longitudinal row of ratchet teeth, a pawl engaging said ratchet teeth for moving the tape lengthwise in one direction, means by which the pawl is reciprocated when the support is oscillated, releasable means for holding the tape from being moved lengthwise in the opposite direction, a spring, and means by which when the said holding means is released from said tape, the spring will retract said tape in said opposite direction.

In testimony whereof I have signed my name to this specification in presence of two subscribing witnesses.

JAMES M. WOOD.
